Application filed December 26, 1900. Serial No. 41,163. Term of patent 7 years.

To all whom it may concern:

Be it known that I, DAVID FRANK, a citizen of the United States, residing at New York, (Brooklyn,) Kings county, State of New York, have invented and produced a new and original Design for an End Frame for Bedsteads, of which the following is a specification, reference being had to the accompanying drawing, forming a part thereof, and in which is represented a perspective view of an end frame for bedsteads bearing and incorporating my design.

In the drawing, A A designate the corner-posts, B B the transverse rods extending intermediate said corner-posts, and C C the usual vertical rods extending intermediate the rods B B. Above the upper rod B is an ornamental field defined by the rod D and enclosing the ornate scroll-rods E F F and G G, the rod E being interposed intermediate the upper rod B and rod D, the rods F F being of corresponding outline and disposed intermediate the rods E D and at opposite sides of the vertical central rod H, and the rods G G being at the ends of the rod E, the whole being substantially as shown. 25

What I claim is—

The design for an end frame for bedsteads, substantially as shown and described. 30
